UNITED STATES PATENT OFFICE.

CHARLES M. STEIN, OF PARIS, FRANCE, ASSIGNOR TO SOCIÉTÉ ANONYME, LA COMBUSTION RATIONNELLE, OF PARIS, FRANCE.

SINGLE-WORKING-CHAMBER TURBOPULVERIZER.

Application filed January 7, 1925. Serial No. 1,081.

To all whom it may concern:

Be it known that I, CHARLES M. STEIN, a citizen of the French Republic, residing at Paris, Department of the Seine, in France, have invented certain new and useful Improvements in Single-Working-Chamber Turbopulverizers; and I do hereby declare the following to be a full, clear, and exact description of the invention, such as will enable others skilled in the art to which it appertains to make and use the same.

The invention concerns pulverizing machines, especially those employed in the production of pulverized coal, whose industrial applications are continuously developing; its principal object being to obtain a type of crusher in which a constant ventilation is maintained, both of the fuel being fed in and of the fuel being crushed, so as to remove all particles which have reached the required degree of fineness, immediately they are formed. Although the description of the method of working is made with the supposition that it is applied to coal, the machine can be used for the pulverization of any other material. In this case the pulverized product in suspension in the air, instead of being blown to the burner, is separated from the air by which it is borne by the well known centrifugal process and can be collected in a storing hopper.

To obtain the results enumerated above, a machine with a single paddle wheel of the usual type was chosen, or for machines of large output, two similar wheels revolving side by side in a single pulverizing chamber. In both cases the method of working is exactly the same, the object of the juxtaposition of the two paddle wheels being solely to increase the production of dust by increasing the number of working parts.

The pulverizer described below is of the rotary type, with crushing paddles or hammers, and is distinguished by the fact that due to the arrangement of its parts, the material undergoing crushing, whatever may be its degree of fineness, is projected in totality and in the form of continuous jet into a separator, whence the dust which is sufficiently fine is evacuated, the particles which are too heavy being returned to the

crusher for the operation to be finished. By means of the continuous circulation in the separator of the product under treatment, the fine particles being immediately removed, do not obstruct the crusher, and the impact of the paddles on the material under treatment is not diminished. The result is evidently an increase in the efficiency of the machine; either an increase in the possible output or a reduction in the power absorbed.

The machine which is the object of the present invention enables the results given above to be obtained, because of the arrangement of the parts of the crusher, rotor and stator, without the necessity of any accessory parts such as ventilators or mechanical handling appliances of any kind.

Fig. 1 is an elevation and part longitudinal cross section of the whole of the machine in accordance with the invention.

Fig. 2 is a side view, part in elevation and part in cross section, of the machine shewn in Fig. 1, the section passing through the vertical transverse plane of the paddle pulverizer.

Fig. 3 is an elevation and part longitudinal cross section of another form in which the machine can be made.

Fig. 4 is a cross section.

Fig. 5 is a side view.

Fig. 6 is another variation of the machine.

Referring to Figs. 1 and 2, on the shaft 1 of the machine, driven by any suitable motor, are keyed the paddles 7 of the crusher, and either at the end of the shaft as shewn in the drawing, or between the bearings, the ventilator wheel or blower 2 for extracting the dust, the said ventilator being connected by piping 6' and 6 to the extraction chamber 13 which covers the upper part of the crusher.

The material to be crushed is fed into hopper 3, and its introduction into the machine is controlled by a distributing appliance 16 of a well known type, it passes through conduit 4 to the inlet orifices of the crusher. To obtain a better result from the operation of the paddles and particularly where a double pulverizing wheel is employed, the device for feeding the crusher with the raw material should be symmetrical with respect to the vertical axis of Fig. 1.

The cover of the crusher has an opening in its upper part to which a tapering nozzle 10 is joined, and through which discharge takes place freely at its upper end, against a reinforced shield 11, prolonged by lateral walls which form two lateral conduits 9—9, discharging in the extraction chamber 13, on each side of the crusher.

The cover 12 of the crusher, the nozzle 10, the shield 11 and the partitions defining the conduits 9—9, form a stator in cast iron, with the necessary joints for erection or inspection purposes. Movable linings are provided at the places exposed to wear. In its lower part the crushing chamber 8 has a recess 14 in communication with a space provided in the base of the machine, this space is fitted with a door for cleaning purposes. The stator 8 is connected at its upper part to a sheet iron separator 5 whose purpose will be described later. This separator is in direct communication with the extraction ventilator 2, by suitable piping 6 and 6'. Openings of adjustable cross section give access to the transporting air at either side of the crushing zone, to the lower part of the extraction chamber 13.

All the product under treatment, already more or less finely pulverized, is carried round by the rapid rotary movement of the paddles and escapes by the upper nozzle 10, is then stopped by the shield 11 and drops down the channels 9—9, on either side of the paddle wheel in the form of two lateral curtains as shewn by the arrows. The air drawn in by the ventilator extracts all the fine fuel from these curtains the heavier pieces falling back into the crusher to undergo once again the action of the paddles.

It is clear from what has been said, that the extraction of the product is done continuously during pulverization, the crusher can therefore only retain coal which will again require to be treated after ventilation.

As the coal is fed in from the distributor, this operation of extracting the dust is also effected, the particles which are sufficiently fine being drawn towards the ventilator.

Further, it can be seen that the air used for extraction does not cross the zone where pulverizing takes place, but merely touches the zone; the high speed of rotation of the paddles is therefore without influence on the power absorbed by the ventilator.

The cross sections of the separator 5 are designed in such a way that the speed of ascension of the transporting air is very slow. Under these conditions the particles which are too heavy cannot cross the zone of small velocity and return by gravity to the pulverizer to undergo further crushing. It is easily conceived that, either by the reduction of the output of the ventilator, or by an increase of the cross sections of the separator, both processes influencing the speed of the

air in the separator, it is possible to obtain the extraction of the finished product with any degree of fineness.

Referring to Figs. 3, 4 and 5; the pulverizing organ is fixed on the shaft 1 of the machine, supported by bearing 1', and driven by any suitable motor, either through the pulley 17 or the coupling 18. The pulverizing organ consists essentially of a hub 19, keyed onto the shaft of the rotor, a disc 20 of heavy steel plate fixed to the hub, the periphery of the disc 20 being cut in such a way as to take the pulverizing hammers 21. These hammers are rigidly bolted onto angle irons which are themselves solidly riveted onto the disc 20; the working face of the hammers can either be radial or make a certain angle with the plane passing through the axis of the rotor.

The pulverizing wheel thus formed, revolves in the interior of a cast iron stator, including a cover whose shape is usually circular, concentric or not to the path followed by the outer edges of the hammers, and two flat ends.

An opening in the cover 22 is joined, tangentially for preference, to an outlet nozzle 23, which allows of the normal discharge of all the product undergoing crushing.

This nozzle 23 which is of rectangular section at its junction with the crushing chamber, may or may not be afterwards transformed into a section of any other shape, square or round for example. The nozzle, shown vertical in the drawing, can be fixed in any other direction if necessary.

The cover 22 also has an opening in its lower part, which puts the pulverizing chamber into communication with a space 24 in the base of the machine and which is intended to collect all hard particles, scrap metal for example, introduced by accident into the crusher together with the material to be treated. A door 25 enables this space to be cleaned out from time to time. The cover of the crusher as well as the lower recess and the outlet nozzle carry a heavy armouring of metal or any other wear resisting material 26—26. The flat ends which limit the crushing chamber laterally are each provided with an opening 27 into which open the spouts 28 which return the residue or particles requiring further crushing, from the separator, on the one hand, and on the other the spouts 30—30, through which the distributor feeds the raw material to be crushed. Adjustable air inlet orifices 31—31, enable the air required to carry off the treated products, to be admitted into the body of the crusher.

It can be seen that the devices described above enable the crusher to work symmetrically in all respects and thus to obtain a greater efficiency. Further, it can be seen that the machine, thus designed, in addition

to its rôle as a crusher, works as a ventilator with its two suction orifices 31—31, a turbine whose hammers 21 form the blades, a volute 22, an interior profile circular or spiral, and a discharge nozzle 23. It follows that the machine described will enable the required object to be attained: to pulverize a material by the impact of the paddles and projection or friction on a resisting cover, the whole of the product under treatment being continuously in suspension in the air and by the sole effect of the construction of the proposed crusher, in the interior of a separator in which the fine dusts will be selected, which the air will carry off towards their point of utilisation, while the remainder will be brought back to the crusher to undergo once again the action of the paddles together with the raw material fed in by the distributor.

In order to render inspection, taking down and changing the crusher parts more easy, the lateral face of the stator on the opposite side to the motor, may be fitted with an opening, circular for preference and closed hermetically by a hinged door.

From the preceding description, it is evident that the machine itself constitutes a complete unit, which, fed by a distributor of a known type, is capable of crushing the raw material by impact or friction, of projecting into a separator all the product previously beaten by the paddles mixed with an adjustable quantity of air, whatever be the degree of crushing already obtained on the product, the said separator being arranged to effect the selection of the particles having the required degree of fineness by means of the current of air created by the rotation of the crusher, which is capable of ensuring the transport of the finished product either to the storing hopper, or in the case of pulverized coal, to the burners of the furnace.

It is evident that this transport of the finished product cannot be effected to a great distance, the characteristics of the rotor and the stator being essentially fixed with a view to the crushing and discharge to the separator. In the case where the receptacle of the finished product is situated at a distance from the machine, it would be possible to effect the transport by means of an auxiliary blower, which could be driven by an independent motor, or by a pulley receiving its motion from the main shaft of the crushing machine, or finally, for greater simplicity, mounted on the shaft of the crushing machine itself, either between the bearings or on a bracket on the opposite side to the pulverizing chamber. The ar-

rangement with independent ventilator has been shewn in dotted lines on the adjoining figures, as an example.

Fig. 6 shews a cross section of a variation of the machine.

The difference between this variation and the arrangements described above, consists in the fact that, owing to a modification in the interior arrangement of the separator, 70 the passage of the residues through the separator is effected by a single ajutage, and that their return to the crusher, instead of being made at the same time as that of the raw material in the central zone of the two lateral 75 faces of the crushing chamber, is made at the periphery of this chamber, through an inlet orifice 32, which is tangential for preference, in a direction opposite to that of the discharge nozzle. 80

The machine can thus still work symmetrically and all that has been said above is exactly applicable to the new arrangement.

In Fig. 6 the paddles have been shewn, as an example with their working faces in a direction which is not radial. It will be evident to any expert that modifications of details can be made to the machine as described, without going beyond the limits of 90 the invention.

What I claim is:

1. A pulverizer comprising a casing having a lateral supply inlet, a rotary pulverizer mounted adjacent said inlet and inducing an air blast through the casing, a discharge nozzle above the pulverizer, a deflecting hood surrounding the nozzle and forming return passages for the material acted upon by the pulverizer, and a discharge outlet for fine material at the top of the 100 casing. 95

2. A pulverizer comprising a casing having a lateral supply inlet, a rotary pulverizer mounted adjacent said inlet and inducing an air blast through the casing, a discharge nozzle above the pulverizer, a deflecting hood surrounding the nozzle and forming return passages for the material acted upon by the pulverizer, a separator connected to the top of the casing, and a 110 fan blower connected to the discharge end of the separator. 105

3. A pulverizer comprising a casing, a rotary pulverizer inducing an air blast through the casing, a discharge nozzle above the pulverizer, a separator above the nozzle, and passages connecting the separator with the casing to return the heavy materials to the pulverizer. 115

In testimony whereof I affix my signature.

CHARLES M. STEIN.
